UNITED STATES PATENT OFFICE.

DAVID CONLAN, JR., OF BROOKLYN, NEW YORK.

ELECTRICAL APPARATUS.

1,400,803.

Specification of Letters Patent. Patented Dec. 20, 1921.

Application filed December 24, 1920. Serial No. 432,983.

To all whom it may concern:

Be it known that I, DAVID CONLAN, Jr., a citizen of the United States, and a resident of Brooklyn, Kings county, and State 5 of New York, have invented certain new and useful Improvements in Electrical Apparatus, of which the following is a specification.

My present invention relates to current 10 extension apparatus for marine and water tight uses.

The objects of the invention are to provide commercially practicable and desirable apparatus of the character referred to, which 15 will be useful for a great variety of purposes.

In the accompanying drawings I have illustrated different practical embodiments 20 of the invention, but wish it understood that such illustration is primarily for purposes of disclosure and that various changes and modifications may be resorted to without departure from the true spirit and scope 25 of the invention as hereinafter defined and claimed.

In the drawings referred to, Figure 1 is a longitudinal sectional view of several of the different units connected in operative 30 relation, certain of the parts appearing in elevation. Fig. 1^a is a fragmentary sectional view illustrating a detail of construction.

Fig. 2 is an enlarged plan view of the second switch unit, which carries the 35 through-circuit and also controls a cord outlet.

Fig. 3 is an enlarged cross sectional view as taken on substantially the plane of line 3-3 of Fig. 1.

Fig. 4 is a detail plan view of the detachable fuse disk. Fig. 4^a is a broken sectional view of the snap fastening for the fuse disk.

In Fig. 1 I have illustrated a set of six 45 of the units joined as detachable elements of a pair of extensible bus bars.

The first element, designated by the reference character A, serves simply as a current outlet, being provided with contacts 50 for engagement by the projecting blades of the second element B which constitutes a "through" switch for controlling the succeeding units. The third unit C carries the elements of the through-circuit and also a 55 switch controlling a cord circuit. The fourth element D is a through-circuit mem-

ber having attached to its blades a fuse disk at E for the protection of the cord circuit extending therefrom. The next element F of the set is a fuse unit carrying cartridge 60 fuses protecting the succeeding units. The next unit G is a through-circuit unit provided with a current outlet to receive the plug of a cord circuit.

The first or primary outlet member 65 comprises a base 15 provided with wire terminals 16 and having insulating sockets 17 in which are located spring terminal contacts 18 for engagement by the blades of the adjoining unit.

This base, like the bases of the succeeding units, is supported in a water-tight casting, which consists in this particular instance of a surrounding sleeve or collar 19 provided at its lower end with an inturned 70 flange 20 for the support of the base and having connected with its upper end a head or cover 21 provided with a screw threaded neck for engagement with the piping of a conduit system. The sleeve element 19 is 75 shown as having a screw threaded lower end 22 to receive the coupling flange 23 of the adjoining unit. This coupling flange or ring is shown as held to the shell 19 of the adjoining unit by a ring 24 screwed onto 80 the upper end of the shell so as to form a shoulder for the inturned flange 25 of the coupling, said ring 24 also having an inwardly extending flange 26 overlying the 85 edge of the insulating base of the unit seated 90 in such shell. As many of the parts described are duplicated in successive units, I have used the same reference characters wherever that has been possible.

The through-circuit controlling switch B 95 is shown as consisting of a push button switch structure having a movable contact 27 operated by push buttons 28 and arranged to bridge the relatively stationary contacts 29, 30, the first of which is connected with one of the projecting blades 31 at one end of the switch and the latter of which is connected with a contact 32 seated in an insulating pocket 33 in the opposite end of the switch and standing in position 100 to be engaged by one of the projecting blades 34 of the succeeding unit. The other projecting blade 35 of the through-circuit controlling switch is shown as directly connected by means of a screw 36 or the like 105 with a terminal contact 37 seated in a recess 38 in the bottom of the switch in position

to be engaged by the other projecting blade 39 of the succeeding unit. The push buttons or operating devices of the switch described are shown as protected by suitable 5 waterproof diaphragms 40 of rawhide or the like.

The water-tight shell of the section described, and in fact the shells of all the sections may be provided with outstanding 10 flanges such as I have shown at 41 above the threaded lower ends thereof to prevent injury to the screw threads as for instance when the devices are knocked about the deck of a ship.

15 The projecting blades 34, 39 by which the unit C is coupled in circuit, are both connected by through screws 42 with current extension terminals 43 seated in insulating sockets in the lower end of this unit and arranged 20 for engagement by the projecting blades 44 of the next unit D. As shown more clearly in Fig. 2, one of the contact blades, 34, is provided with a binding post 45 to receive one wire of the cord circuit 46 and the 25 other wire of the cord circuit is connected with a binding post 47 which is electrically connected as by means of a screw 48 with the switch mechanism indicated generally at 49, the other side of said switch mechanism being connected as by means of the screw 50 with the base of the other contact blade 39. In this manner a continuation circuit is provided 30 through the unit and the switch which it carries controls a branch outlet or cord circuit for an exploration lamp or the like. A gland or suitable water-tight packing is shown provided at 51 where the cord 46 leaves the water-tight casing.

The through-circuit unit D like the preceding 40 unit has sockets in its lower end containing terminal posts 52 connected with the projecting blades 44 at the upper end thereof. This unit also has a cord outlet, as I have indicated at 53, and this cord circuit is protected 45 by fuse links 54 (Fig. 4) carried by a disk or concealed between disks 55 of insulating material which have eyelets 56 to fit over and make electrical contact with the connecting-in blades 44 and elements 57 similar to 50 one of the members of a so-called snap fastener which engage corresponding interfitting elements 58 on the terminal plates 59 which are provided with binding posts 60 for the cord circuit leading off at 53.

55 The fuse links are connected between the blade eyelets 56 and the elements 57 of the snap fastenings so that when the disk is pushed down over the blades and the snap fastenings interlock, current will be transmitted 60 to the terminal plates and hence to the wires of the cord circuit connected therewith, this branch circuit being then protected by the fuses. This construction enables the ready substitution of new fuses by simply slipping the old fuse disk off the connect-

ing-in blades and replacing the same with a new fuse disk.

At the extension unit F the through-circuit is fused by means of cartridge fuses 61 seated in sockets in the insulating base of this member and electrically connected at their upper ends with the connecting-in blades 62 and electrically connected at their lower ends with the circuit extension contacts 63 seated in the insulating sockets in the lower end of this unit. These fuses are shown as resting on springs 64 at their lower ends electrically connected with the extension terminals and as held in their sockets at the upper ends by the screw 65 in electrical connection with the bases of the connecting-in blades 62.

The last of the through-circuit units shown in Fig. 1 has a pair of the connecting-in blades 66 at the upper end thereof and is provided as in the preceding cases with current extension terminals 67 in insulating sockets in its lower end to enable the connection of other units in circuit. This member has a branch outlet consisting of a pair of plates 68, arranged to receive the projecting blades 69 of the attachment plug 70 of the cord circuit and electrically connected with the through connectors 71 of this member. When no more units are to be added, the 95 sockets in the end of the last member may be protected by a water-tight cap 72 screwed onto the lower threaded end of the last casing.

The example given is just one illustration of the way in which the units may be coupled and it will be understood that these units may be connected in many different relations to meet various requirements. The first switch unit controls the through-circuit and hence controls the circuit of any and all succeeding units which may be coupled thereto. The second switch unit on the other hand merely controls the cord or branch circuit led off therefrom and provides through connections for the next member. The branch 110 circuit member D provides a through connection and by reason of the detachable fuse disk and the special connections associated therewith protects the branch circuit. The unit F which is plugged into the unit D provides 115 fuses in both sides of the through-circuit so that the succeeding unit or units are coupled in on a fused line. This is quite desirable where the units are extended beyond a certain point. The last unit shown 120 (G) provides through-circuit connections (not utilized in this particular case) and a branch outlet receiving the blades of an attachment plug. This outlet may receive the blades of any of the other units illustrated and described. For instance, if the cord circuit at this point were to control a soldering iron or the like, one of the through-circuit controlling switches such as illustrated at B might be interposed at this point 130

to afford a ready means of cutting the iron into and out of circuit.

From the foregoing it will be apparent that the invention provides simple and entirely practical means for extending a circuit so far as may be required by simply plugging one device into another and that these several units may be utilized for the various purposes of controlling the succeeding portions of the through-circuit, to provide branch circuits, which may be switch-controlled or not, as desired; and to fuse either the through-circuit or the branch circuits, etc., and that as said units are readily interchangeable, various combinations can be easily effected to suit different requirements. The marine fittings have the advantage that the units are mechanically coupled together so that any separating strains will be taken care of by these mechanical connections, thereby relieving the electrical plug connections of all strain. I have not attempted to show all the uses to which the invention may be put or all the various ways in which it may be modified, and I therefore wish it understood that the terms which I have used in disclosing and claiming this invention are used in a descriptive rather than in a limiting sense, except as may be required by the prior art.

What I claim is:

1. A continuous electrical outlet comprising a sectional tubular casing, of short casing sections connected by means providing readily separable water-tight joints, insulating bases secured in said casing sections with their opposite ends exposed at the opposite ends of the respective sections, circuit-continuing connections extending through said bases and complementary connecting-in contacts and through-circuit terminals at the opposite exposed ends of the individual bases and in circuit with said through-connections, the water-tight connecting means of the casing sections being constructed to enable the electrical engagement of the complementary contacts and terminals when adjacent casing sections are coupled together.

2. A continuous electrical outlet comprising a sectional tubular casing, of short casing sections connected by means providing readily separable water-tight joints, insulating bases secured in said casing sections with their opposite ends exposed at the opposite ends of the respective sections, circuit-continuing connections extending through said bases and complementary connecting-in contacts and through-circuit terminals at the opposite exposed ends of the individual bases and in circuit with said through-connections, the water-tight connecting means of the casing sections being constructed to enable the electrical engagement of the complementary contacts and terminals when adjacent casing sections are coupled together, one of said

casing sections having means providing a water-tight branch circuit outlet and one of the insulating bases having branch terminals for said outlet.

3. A continuous electrical outlet comprising a sectional tubular casing of short casing sections provided with shoulders and connected by means providing readily separable water-tight joints, insulating bases supported on the shoulders within said casing sections with their opposite ends exposed at the opposite ends of the respective sections, circuit-continuing connections extending through said bases, connecting-in blades and complementary through-circuit socket terminals at the opposite exposed ends of the individual bases and in circuit with said through-connections, the water-tight connecting means of the casing sections being constructed to enable the engagement of the complementary blades and socket terminals when adjacent casing sections are coupled together.

4. A continuous electrical outlet comprising a sectional tubular casing, of short casing sections, each of said casing sections provided at its opposite ends with the complementary parts of a readily detachable water-tight coupling for mechanically securing together adjacent casing sections in water-tight relation, insulating bases secured in said casing sections with their opposite ends exposed at the opposite ends of the respective sections, circuit-continuing connections extending through said bases and complementary connecting-in contacts and through-circuit terminals at the opposite ends of the individual bases and in circuit with said through-connections, the complementary members of the water-tight coupling means being constructed to enable electrical engagement of the complementary contacts and terminals when adjacent casing sections are coupled together in their water-tight relation.

5. A continuous electrical outlet comprising a sectional tubular casing, of short casing sections, each of said casing sections provided at its opposite ends with the complementary parts of a readily detachable water-tight coupling for mechanically securing together adjacent casing sections in water-tight relation, insulating bases secured in said casing sections with their opposite ends exposed at the opposite ends of the respective sections, circuit-continuing connections extending through said bases and complementary connecting-in contacts and through-circuit terminals at the opposite ends of the individual bases and in circuit with said through-connections, the complementary members of the water-tight coupling means being constructed to enable electrical engagement of the complementary contacts and terminals when adjacent casing sections are coupled together.

sections are coupled together, a primary outlet unit having a casing provided with a coupling member complementary to the coupling members of the other casing units and containing terminals for a feed circuit with electrically connected through-circuit terminals complementary to the connecting-in contacts of other casing sections and a water-tight cover unit having a coupling member complementary to the coupling members of other casing sections and the coupling member of the primary outlet casing section, whereby said cover may be applied as a water-tight closure either direct 10 to the primary outlet casing or to the end 15 of a casing section coupled to the primary outlet casing.

6. A water-tight electrical connecting unit comprising a tubular casing section having the complementary members of a water-tight coupling at the opposite ends thereof, an insulating base secured in said casing section with its opposite ends exposed at the opposite ends of said section, circuit continuing connections extending through said base and complementary connecting-in contacts and through-circuit terminals on the opposite exposed ends of the base and in circuit with said through-connections, branch

circuit terminals on the base, the casing section having an outlet for said branch circuit terminals and a water-tight packing at said branch outlet. 30

7. A continuous electrical outlet comprising insulating bases in end-to-end relation, 35 means mounting the respective bases and connected in watertight inclosing relation thereto, complementary connecting-in contacts and through-circuit terminals at the opposite ends of the respective insulating bases and electrically connected to provide through-circuit connections when adjoining bases are coupled together in their watertight relation, a primary outlet unit provided with terminals for feed circuits, electrically connected through-circuit terminals complementary to the connecting-in contacts 40 of other units and water-tight coupling means complementary to the coupling means of other units, to thereby enable the 45 coupling of such other units to said primary outlet unit and a water-tight cover provided with coupling means complementary to the coupling means of said primary outlet unit and of the several sections aforesaid. 50

In witness whereof, I have hereunto set my hand this 22nd day of December, 1920.

DAVID CONLAN, JR. 55
